SLIDE SUPPORT

Filed Dec. 27, 1922

FIG. 2.

FIG. 1.

Arthur C. Lindholm, INVENTOR.

BY

Frank A. Cutler, ATTORNEY.

FIG. 4.

FIG. 5.

UNITED STATES PATENT OFFICE.

ARTHUR C. LINDHOLM, OF SPRINGFIELD, MASSACHUSETTS.

SLIDE SUPPORT.

Application filed December 27, 1922. Serial No. 609,828.

To all whom it may concern:

Be it known that I, ARTHUR C. LINDHOLM, a citizen of the United States of America, and a resident of Springfield, in the county of Hampden and State of Massachusetts, have invented a new and useful Slide Support, of which the following is a specification.

My invention relates to improvements in means for carrying and guiding slides upon which are mounted work- or tool-holding chucks, or other more or less similar elements, of grinding machines and the like, and consists essentially of parallel rods supported on or in the bed of the machine, a slide having lugs mounted on said rods and supporting the slide above the top of said bed, adjustable friction means between said slide and rods, and actuating means for said slide, together with such other parts and members as may be necessary or desirable in order to render the device complete in every respect, all as hereinafter set forth.

The primary object of my invention is to produce a slide support, of the character described above, which, not only is comparatively simple and inexpensive in construction, and strong and durable, but holds and guides the slide with great accuracy, the latter being a very important factor in the type of machine for which this slide support is adapted, inasmuch as lost motion in such a slide is often fatal to the successful operation of the machine.

Another object is to provide the slide support with adequate means for taking up wear and thus keeping the reciprocable members tight or maintaining the proper sliding fit, and also for producing the desired degree of tension on the moving parts, whereby is facilitated at all times the act of setting of the slide by means of the hand screw.

My slide support is especially adapted for portable grinders or grinding machines for automobile repair work, although the same is by no means limited to such machines.

Other objects and advantages will appear in the course of the following description.

I attain the objects and secure the advantages of my invention by the means illus-

trated in the accompanying drawings, in which—

Figure 1 is a top plan of a fragmentary portion of the bed of a grinder, which bed is equipped with a slide support that embodies a practical form of my invention; Fig. 2, a bottom plan of said slide support and other parts and members shown in the preceding view; Fig. 3, a transverse, vertical section through the slide support and other parts and members, taken on lines 3—3, looking in the direction of the associated arrow, in Fig. 4; Fig. 4, a central, vertical, longitudinal, section through said slide support and parts and members, and, Fig. 5, a sectional detail illustrating one of the friction devices.

Similar reference characters designate similar parts throughout the several views.

In the drawings, a fragmentary, corner portion of the bed of a grinder is represented at 1, and a slide, at 2, for the chuck-supporting members of said grinder, said slide being arranged above said bed. There are openings 4 and 5 in the bed 1, which openings are separated by a cross-piece 6 that is an integral part of said bed. The opening 4 is in front of the opening 5. The bed 1 is provided at the forward end with a pair of bearing lugs 7 and a bearing 8, the latter being between the two bearing lugs. These bearing members open at their front ends through the front edge of the bed 1, and at their rear ends into the opening 4. The bed 1 is further provided with a pair of bearing lugs 7 behind the first pair. The rear bearing lugs 7 open at their front ends into the opening 5, and at their rear ends through a depending part of the bed, as indicated by dotted lines in Figs. 2 and 4. The axis of each rear bearing lug 7 is in the same straight, horizontal line with the axis of the corresponding front bearing lug 7.

A horizontal, actuating screw 9 extends through the bearing 8 and through a bearing provided for the same in the cross-piece 6. A hand-wheel 10 is secured to the front, protruding terminal of the screw 9, the hub of which wheel bears against the front edge of the bed 1. On the rear, protruding terminal of the screw 9, behind the cross-piece 6, is a washer 11 and a nut 12. Thus the screw

9 is held against longitudinal movement in its bearings by the hub of the hand-wheel 10 and the washer 11 and nut 12.

Two parallel, horizontal, supporting and 5 guide rods 13 are arranged in the bearing lugs 7. The rods 13 may be secured in their bearing lugs with a driving fit.

On the under side of the slide 2 are a long, transverse lug 14 and a pair of short lugs 15, 10 the former being in front of the cross-piece 6 in the opening 4, and the latter behind said cross-piece in the opening 5. These lugs are so positioned beneath the slide 2 as to permit said slide to be moved lengthwise to the 15 required extent before said lugs contact with the front and rear boundaries of the openings 4 and 5. The lug 14 is bored to receive the rods 13, and so, also, are the lugs 15, the arrangement of the three lugs and the four 20 bores therein necessarily being such that said rods can pass through the lugs. The lug 14 is further bored to receive the actuating screw 9, the passage through said lug for said screw being in the center of the lug, and 25 inferiorly screw threaded for engagement with the screw. The lugs 14 and 15, when mounted on the rods 13, support the slide 2 above and preferably clear of the upper surface of the bed 1, and said lugs are adapted 30 to slide on said rods, the sliding action being produced by turning the hand-wheel 10 and thus revolving the screw 9. When the hand-wheel 10 is revolved in one direction, the screw 9, which is in threaded engagement 35 with the lug 14, actuates said lug and with it the slide 2 forwardly, and when said hand-wheel is rotated in the opposite direction, said screw causes said lug and slide to be moved rearwardly, the lugs 15 sliding 40 with said first-named lug on the bars 13.

One or more friction devices, each preferably consisting of a screw 16 and a bearing member 17, are provided for the slide 2, whereby the lugs 14 and 15 are caused to engage the rods 13 with a greater or less degree of tightness or force, and more or less frictional resistance to the movement of said lugs on said rods is produced—see Fig. 5. Each screw 16 is tapped into a vertical opening or passage 18 in the slide 2, which passage extends downwardly into either the bearing 14 or one of the bearings 15, and is positioned directly over the rod 13 which extends through the bearing. In other words, 50 the passages open at their lower ends into the bores for the rods 13 in the bearings 14 and 15. The friction member 17, in each case, preferably consists of a fiber plug which is inserted in one of the passages 18 beneath the screw 16 in such passage, and 55 between said screw and the rod 13 below.

Upon turning down any one of the screws 16 the plug 17 below is forced more tightly against the contiguous rod 13, and so increases the resistance offered to the move-

ment of the lug, in which said screw is located, on said rod; contrariwise, upon turning said screw upwardly, such resistance is decreased. In addition to the variable frictional resistance afforded by the screws 16 and the plugs 17, said screws and plugs are useful in taking up any wear that may result from the action of the lugs 14 and 15 on the rods 13, and to maintain the requisite tight fit between said lugs and rods.

The detailed functions of the slide 2 are not important, so far as the present invention is concerned, hence will not be explained, and the operation of said slide, through the medium of the screw 9, will be clearly understood from the foregoing description.

The rods 3, when properly arranged and secured in place beneath or within the bed 1, provide combined supports and guides for the slide 2, through the medium of the lugs 14 and 15 which are integral with said slide, which are of such a nature that said slide is supported and guided with the utmost accuracy and without liability of being impaired so far as the supporting and guiding means therefor are concerned. The rods 13 and the lugs 14 and 15 securely hold the slide 2 against movement in any direction except longitudinally of said rods.

Generally the screws 16 are turned down sufficiently to produce a slightly appreciable resistance, over and above that which would naturally be present, to the action or thrust in either direction of the screw 9.

More or less change in the shape, size, construction, and arrangement of some or all of the parts of this slide may be made, without departing from the spirit of my invention, or exceeding the scope of what is claimed.

What I claim as my invention, and desire to secure by Letters Patent, is—

1. The combination, in a slide support, with a bed provided with a cross-piece and with a bearing and two pairs of bearing lugs, said cross-piece being between said pairs of lugs, rods secured in said lugs, an operating screw journaled in said bearing and said cross-piece, and means to hold said screw against endwise movement, of a slide provided with lugs adapted to be mounted on said rods and for threaded engagement with said screw.

2. The combination, in a slide support, with a bed provided with bearing lugs, and rods, secured in said bearing lugs, of a slide provided with lugs mounted on said rods, and further provided with adjustable engaging means for one of said rods, whereby the resistance to the movement of said slide on such rod may be increased or decreased.

3. The combination, in a slide support, with a bed provided with bearing lugs, and rods secured in said bearing lugs, of a slide

provided with lugs mounted on said rods, and having a tapped passage opening onto one of said rods, a screw in said passage, and a plug in said passage between said

5 screw and the adjacent rod.

4. The combination, in a slide support, with a perforated bed provided with a cross-piece and with a bearing and bearing lugs, rods secured in said bearing lugs, an operating screw journaled in said bearing and said

10 cross-piece, and means to hold said screw against endwise movement, of a slide pro-

vided with lugs adapted to be mounted on said rods and for threaded engagement with said screw, said slide and its lugs having 15 passages tapped therein to open onto said rods, screws in said passages, and plugs in said passages between said screws and said rods.

ARTHUR C. LINDHOLM.
